Patented Oct. 5, 1976

241,737

STORM SHELTER

Jack L. Stout, 1209 Kouba Drive,
Yukon, Okla. 73099

Filed Feb. 24, 1975, Ser. No. 552,305

Term of patent 14 years

Int. Cl. D25—03

U.S. Cl. D25—36

FIG. 1

FIG. 2

FIG. 1 is a side elevation view of a storm shelter showing the present design, the opposite side elevation view being identical in appearance but opposite hand;

FIG. 2 is a top plan view of the present design;

FIG. 3 is a bottom plan view of the present design;

FIG. 4 is a rear elevation view of the present design as viewed from the left in FIG. 1; and

FIG. 5 is a front elevation view of the present design as viewed from the right in FIG. 1.

I claim:

The ornamental design for a storm shelter, substantially as shown and described.
